BOX FOR FACE POWDER AND SIMILAR MATERIAL

Application filed March 9, 1932. Serial No. 597,840.

An object of the invention is to provide a box having inner and outer walls, the space between the inner and outer walls being covered by a member with a central opening, 5 the sides of the said member diverging upwardly from the inner wall to the outer wall to form an upwardly diverging flange around the top of the inner wall which serves to retain within the box powder which may fall 10 from a powder puff as it is removed from the powder within the inner wall of the box.

Another object of the invention is to provide the member covering the space between the inner and outer walls with a wall disposed at the inner side of the said inner wall, the said wall on the member and the said inner wall having apertures which register when the member is in one position relatively to the inner wall, thereby permitting powder 20 to pass from the space between the inner and outer walls, it being possible to move the member relatively to the said inner wall to close the apertures in the said inner wall.

Additional objects of the invention will 25 appear in the following specification in which the preferred form of the invention is described.

In the drawing similar reference characters refer to similar parts in all the views, of 30 which

Figure 1 is a sectional elevation showing the invention.

Figure 2 is a sectional view on the line 2—2 of Figure 1,

Figure 3 is a perspective view of the box, and

Figure 4 is a sectional elevation showing a modified form of the invention.

By referring to the drawing it will be seen 40 that the box has a base 5 and a peripheral circular enclosing wall 6 provided at its bottom with a flange 7 secured to the periphery of the base 5. The box also has a circular enclosing wall 8 disposed within the peripheral circular enclosing wall 6 and spaced therefrom, the bottom of the enclosing wall 8 having a flange 9 by which it is secured to the base 5. It will be understood that a space 45 10 is formed between the wall 8 and the wall 6 in which the powder 11 may be disposed.

The said space 10 is normally enclosed by a member 12 which has a depending flange 13 engaging the outer sides of the peripheral circular enclosing wall 6, the sides of the member 12 converging downwardly from the 55 sides of the flange 13 to a point 14, when the sides of the member 12 then extend downwardly to positions in close proximity to the base 5 forming a wall 14'. There are apertures 15 in the member 12 adjacent the base 60 5 and there are also apertures 16 in the circular enclosing wall 8 which are disposed for registering with the apertures 15, it being possible, however, to rotate the member 12 65 relatively to the enclosing wall 8 and the remainder of the box, so that the apertures 15 will be disposed at the sides of the apertures 16, thereby closing the apertures 16 with portions of the member 12 disposed at the sides of the apertures 15. 70

It will be understood that, in using the box, the member 12 may be removed from the remainder of the box, so that the powder may be disposed in the space 10 between the enclosing walls 6 and 8, when the member 12 will be positioned on the enclosing walls 6 and 8, as illustrated in Figures 1 and 3. The member 12 may be rotated so that the apertures 15 will register with the apertures 16, 75 when the powder will pass through the said apertures into the central portion of the box and the passage of the powder through the apertures may be expedited by shaking the box laterally. When sufficient powder is disposed within the central portion of the box, 80 the member 12 may be rotated to close the apertures 16 in the enclosing wall 8, as has been stated. 85

When using the box with the powder disposed in the central portion of the box, a powder puff, or other article or device, may be employed to remove some of the powder from the central portion of the box and, as the powder puff, or other article or device, is lifted from the box, some powder will drop therefrom and this powder will fall on the member 12 at its inwardly converging sides, the said powder being in this way prevented from falling on the table, bureau, or the floor. It will be understood that the box 95 100

will be enclosed by a cover of any desired construction.

In the modified form of the invention illustrated in Figure 4, there is a base 17 from which extends upwardly a peripheral circular enclosing wall 18, the said wall 18 having a flange 19 by which it is secured to the periphery of the base 17, there being an additional member 20 having a flange 21 engaging the outer side of the wall 18, the sides of the member 20 converging downwardly from the sides of the flange 12 to a point 22, when the member 20 extends downwardly substantially parallel with the wall 18 to form a circular enclosing wall 23. In this form of the invention the powder will be disposed on the base 17 and within the wall 22 and, when the powder is removed from the box with a powder puff, or other article or device, any powder falling therefrom will be deposited on the downwardly converging sides of the member 20, so that the powder will fall within the box and not on other surfaces.

What is claimed is:

1. A box for powder and similar materials having a base and a peripheral enclosing wall extending upwardly from the base, an enclosing wall disposed within the first mentioned wall and spaced therefrom, the first mentioned wall extending upwardly from the base at a distance greater than the distance at which the second mentioned wall extends above the base, and a member covering the space between the two walls which extends upwardly and outwardly from the second mentioned wall to the first mentioned wall the member being secured to the second mentioned wall and having a depending flange engaging the outer side of the first mentioned wall.
2. A box for powder and similar materials having a base and a peripheral enclosing wall extending upwardly from the base, an enclosing wall disposed within the first mentioned wall and spaced therefrom, the first mentioned wall extending upwardly from the base a greater distance than the second mentioned wall, a member movable relatively to the first and second mentioned walls and covering the space between the said two walls which extends upwardly and outwardly from the top of the second mentioned wall to the top of the first mentioned wall, and a wall depending from the member adjacent the second mentioned wall, the second and third mentioned walls having apertures which register when the member is in a predetermined position relatively to the second mentioned wall, the member at the end of the third mentioned walls being rotatable relatively to the base and the first and second mentioned walls.
3. A box for powder and similar materials having a base and a peripheral enclosing circular wall extending upwardly from the base, an enclosing circular wall disposed within

the first mentioned wall and spaced therefrom, the first mentioned wall extending upwardly from the base a greater distance than the second mentioned wall, a member movable relatively to the first and second mentioned walls and covering the space between the said two walls and which extends upwardly and outwardly from the top of the second mentioned wall to the top of the first mentioned wall, and a circular wall depending from the member adjacent the second mentioned wall, the second and third mentioned walls having apertures which register when the member is in a predetermined position relatively to the second mentioned wall, the member at the end of the third mentioned walls being rotatable relatively to the base and the first and second mentioned walls.

4. A box for powder and similar materials having a base and a peripheral circular enclosing wall extending upwardly from the base, an enclosing circular wall disposed within the first mentioned wall and spaced therefrom, the first mentioned wall extending upwardly from the base a greater distance than the second mentioned wall, a member rotatable relatively to the first and second mentioned walls, the member having a depending flange at the outer side of the first mentioned wall and a depending circular wall at the inner side of the second mentioned wall, the second and third mentioned walls having apertures which register when the member is in a predetermined position relatively to the second mentioned wall, the member at the end of the third mentioned walls being rotatable relatively to the base and the first and second mentioned walls.
